UNITED STATES PATENT OFFICE.

WESLEY W. GARY, OF BOSTON, MASSACHUSETTS.

RAILWAY-SIGNAL.

SPECIFICATION forming part of Letters Patent No. 257,819, dated May 9, 1882.

Application filed April 21, 1881. (No model.)

To all whom it may concern:

Be it known that I, WESLEY W. GARY, of Boston, in the county of Suffolk and State of Massachusetts, have invented certain Improvements in Railway-Signals, of which the following is a specification.

This invention relates to magneto electric generators designed more particularly for use in connection with railway-signals, the generator being adapted to be set in motion by the passing train.

The object of my invention is to drive the generator by the train in a positive manner without the employment of the intermediate gearing hitherto required, and this without subjecting the apparatus to violent or dangerous shocks or strains.

To this end the invention consists primarily in the use of a rotary generator, arranged to be set in motion by the direct action of the train, and free to continue its forward motion until its momentum is exhausted.

Hitherto it has been attempted to drive rotary magneto-machines from passing trains by means of an intermediate train of gearing, by means of which a high speed was to be imparted to the generator. In practice, however, it has been found impossible to drive generators by the train of gearing, the apparatus having been destroyed or rendered inoperative by the shock of rapidly-passing trains in every instance in which its use has been attempted. It is to overcome this difficulty, and at the same time dispense with the costly gearing, that my invention is designed.

Referring to the accompanying drawings, Figure 1 represents a perspective view of my apparatus in its simplest form. Figs. 2 and 3 are detailed views, illustrating two forms 40 of the yielding sections at the outer ends of the main operating arms.

Referring to Fig. 1, A represents one rail of a railway-track; B, my generator or magneto-machine arranged by the side of the track in position to be acted upon by the train. The generator consists of a fixed permanent magnet, *a*, and a vertical shaft, *b*, provided with the electro-magnets or induction-coils *c*, and with radial arms *d*, the latter being arranged 50 in such position that the trains in passing the

generator will encounter the ends of the arms, and thereby impart to the shaft and its electro-magnets *c* a rapid rotary or spinning motion. The rotation of the electro-magnets in close proximity to the polls of the permanent magnet causes an induced current of electricity in the coils of the electro-magnets in the usual and well-known manner. From the coils connections are made in the manner shown, or in any other ordinary manner, for the transmission of the current to the conductors *e*, which will be extended to a signal or other apparatus to be operated.

In order to prevent the arms *d* from striking violently against the side of the train when the generator is in motion, their outer ends should be jointed or provided with spring-extensions, as indicated in the drawings, which will yield in a backward direction. The spring-extension of the arms will also serve the additional purpose of reducing the shock or jar which occurs as the arms are driven forward by the train.

Referring to Fig. 3, it will be seen that the elastic extension *d* of the arm is secured thereto at a distance from the outer end of the latter. The spring consequently receives on one side a support much nearer its outer end than on the other side. This construction permits the spring to yield readily to an unlimited extent in the backward direction, but permits the yielding motion to a limited extent only in a forward direction. The result is that trains moving backward will pass by the spring-arm readily, while trains moving forward will cause the spring to move the main arm to which it is attached.

A spring-connection or buffer of any suitable character may be introduced at any point in the apparatus or applied to the train for the purpose of reducing the shock as the train acts upon the arms.

It will be noticed that the generator constructed as above described is capable of turning forward independently after being set in motion and until it is brought to a state of rest by natural causes, this mode of action being advantageous in that the motion of the generator and the operation of the instrument connected therewith will continue for a consid- 100

erable length of time after the passage of the train. In order to increase the length of time which the generator will continue in motion, it may be provided with a balance-wheel, as 5 represented in the drawings, or its equivalent, by which the parts are given the required momentum when in motion.

While the forms of apparatus above represented are considered the most desirable for 10 ordinary use, they may be modified to any extent desired without departing from the limits of my invention, provided they are constructed without gearing and are such as to cause the transmission of a positive rotation to the generator from the train and permit the generator to continue its forward rotation without interruption. 15

Any suitable spring or yielding medium may be employed to relieve the parts from 20 shock.

I do not claim herein, as any part of the present invention, the application of a fly-wheel or equivalent weight applied to prolong the motion of a magneto-generator actuated from 25 passing trains, as the same will be made the subject of a separate application.

The form of generator herein represented I 30 denominate a "rotary" generator, in order to distinguish the same from those generators in which one of the members has a vibratory motion with reference to the other, and which are commonly known in the art as "vibratory" generators. By the direct action of the train upon the generator, as herein stated, I mean 35 an action by which the generator is driven

positively from the train as contradistinguished from those generators in which the train sets or adjusts for action a driving mechanism which operates the generators after the passage of the train.

Having thus described my invention, what I claim is—

1. In combination with a railway, a rotary magneto-generator and an arm which imparts motion directly to said generator, said arm, 45 constructed and arranged substantially as described, to be operated directly by passing trains.

2. In combination with a rotary magneto-generator, an operating-arm applied directly to the shaft or arbor of its armature and arranged to be driven by the direct action of 50 passing trains.

3. In combination with a rotary magneto-generator, a driving-arm applied directly to 55 its shaft or arbor, said arm being constructed to yield in a backward direction without affecting the generator and arranged to be operated by the direct action of passing trains.

4. In combination, with the magneto-generator and its operating-arms arranged to be operated by passing trains, yielding sections applied to said arms and adapted to yield 60 freely in one direction and to a limited extent in the opposite direction, substantially as described and shown.

WESLEY W. GARY.
